UNITED STATES PATENT OFFICE.

JAY L. REYNOLDS, OF SPOKANE, WASHINGTON, ASSIGNOR TO REYNOLDS BASE-BALL
PITCHING MACHINE CO., OF SPOKANE, WASHINGTON, A CORPORATION.

BALL-THROWING APPARATUS.

1,201,626.

Specification of Letters Patent. Patented Oct. 17, 1916.

Application filed December 28, 1914. Serial No. 879,254.

To all whom it may concern:

Be it known that I, JAY L. REYNOLDS, a citizen of the United States of America, residing at Spokane, in the county of Spokane, and State of Washington, have invented certain new and useful Improvements in Ball-Throwing Apparatus, of which the following is a specification.

This invention pertains to ball tossing apparatus and has for its object to provide a mechanical means for throwing a ball to be either batted or caught in imitation of baseball throwing, batting and catching.

A further object is to provide a means for tossing the ball at varied rates of speed as may be desired.

A further object is to provide means for tossing the ball at varied and different angles as may be desired.

20 A further object is to provide means for tossing the ball so as to give the same a down, upward, right-hand or left-hand curve as may be desired.

25 A further object is to provide a means for stopping the ball after it has been batted and for conveying the same to a magazine for reentering the ball tossing mechanism.

30 A further object is to provide means for feeding the balls to the ball tossing mechanism as desired.

35 A further object is to provide a signal to indicate to the batter or catcher about the time the ball will emerge from the ball tossing mechanism.

40 Other and further objects and purposes will be hereinafter described and illustrated in the accompanying drawings, in which—

Figure 1, is a vertical sectional view of the ball tossing mechanism taken on the line $a-a$ of Fig. 2, Fig. 2, is a transverse vertical sectional view taken on the line 2—2 of Fig. 1, Fig. 3, is a detail side elevation of the hub and arms shown in Figs. 1 and 2, Fig. 4, is a detail front elevation of the hub and arms shown in Figs. 1 and 2 together with a horizontal shaft connected with said hub carrying band wheels, Fig. 5, is an enlarged sectional view taken on the line 5—5 of Fig. 1, Fig. 6, is a side elevation of the ball tossing mechanism together with the ball magazine,

ball elevator and portions of the detail construction for operating the same, together with a broken-away sectional view of an alley floor, Fig. 7, is a broken-away side elevation of the ball magazine showing a gate mechanism for retaining and releasing the balls therein, Fig. 8, is a broken-away view of an elevator belt showing cups thereon for retaining the balls, Fig. 9, is a broken-away view of the casing of the ball tossing mechanism showing a shoe thereon and mounted rollers upon which the same rests, Fig. 10, is a broken-away view of a canvas map representing a base-ball field together with a view of the end of the barrel of the ball tossing mechanism shown in an opening therethrough and a side elevation of a signal disk for covering the opening leading to the barrel and to signal the time the ball is about to be tossed, Fig. 11, is a detail view of the signal disk together with the connecting mechanism with which the disk is operated to open and close the opening in the canvas leading to the entrance to the barrel of the ball tossing mechanism, Fig. 12, is a front elevation of the ball tossing mechanism together with the shaft and belt-wheels connected therewith and a pedestal and other supporting means for the same. Fig. 13, is a front elevation of the carrier of the ball elevator together with the shafts supporting the same and band-wheels thereon, Fig. 14, is a side elevation of the ball tossing mechanism together with the ball elevating mechanism, a sectional view of the canvas representing a base-ball field, a broken-away sectional view of an alley floor and a portion of the operating mechanism, Fig. 15, is a front view of a canvas indicating a base-ball field together with a view of the end of the barrel of the ball-tossing mechanism shown through an opening in the canvas at a location thereon indicating the pitcher's box and a sectional view of the front end of the alley floor, and Fig. 16, is a side elevation of the ball tossing mechanism including the ball elevator and magazine, a broken-away sectional view of the canvas representing a base-ball field and of the alley floor together with a view of the mechanism for altering the position of the ball tossing mechanism and for operating the gate to feed the balls to the ball tossing mechanism, and a view of a screen between the operating lever and the home or batter's

base. Fig. 17 is a sectional view taken on the line 17—17 of Fig. 18 and Fig. 18 is a broken-away side elevation partly in section of the ball tossing mechanism.

5 Referring now to the details of construction, an upright casing 17 (Fig. 1) preferably somewhat circular in form with variations to meet the requirements is provided with a shoe 18 set upon rollers 19 mounted upon bearings 20. At the center of the casing 17 are openings 21 in which is mounted a hub 22 having arms 23 radiating therefrom. Extending from the opening 21 at the center of the casing 17 to the circumference thereof on both inside walls 17^a and 17^b thereof is a spiral groove 24 in the form of a "spiral of Archimedes" terminating at the upper portion of the casing 17 and connecting with a tangentially arranged barrel 25. 10 The arms 23 occupy a position between the walls 17^a and 17^b of the casing 17 and are of sufficient length to pass over the spiral grooves 24 and reach for a distance into the tangentially arranged barrel 25 connected 15 with the said spiral grooves as shown at 23^a. At the mouth of the barrel 25 and in the inner surface thereof are cut horizontal and parallel oblong grooves 26 in which are mounted fibrous strips 27 secured to a rigid 20 base 28. Extending through the casing of the barrel 25 and reaching to the grooves 26 are openings 29 through which extend pins 30 which are attached to the base 28. Secured to the outer wall of the barrel portion 25, as at 31, are brackets 32 to which are pivoted, as at 33, bell-crank levers 34 to which are pivoted the pins 30, as at 35. Connecting the ends 34^a of the levers 34 with the brackets 32 are coil springs 36. Connected with the ends 34^a of the levers 34 are 25 cables 37.

30 The hub 22 is composed of parts 22^a and 22^b spaced apart by segments 42 and bolted or riveted together as at 41 (Fig. 4) with the arms 23 secured between the segments 42, leaving an opening 42^a between the parts 22^a and 22^b of the hub 22 and between the inner ends of the arms 23. Attached to the side 22^a of the hub 22 is a horizontally arranged 35 shaft 38 carrying band-wheels 39 and 39^a. The side 22^b of the hub 22 has an opening 40 centrally disposed therethrough of sufficient dimensions to permit of the passing of a base-ball. The arms 23 are preferably 40 made of two parallel parts 23^a and 23^b and separated by the segments 43.

45 Referring now to Figs. 6, 7 and 8, connected with the opening 40 of the hub portion 22^b is a magazine 44 cylindrical in form, of a sufficient diameter to carry a base-ball and of sufficient length to contain a number of balls, or as many as may be desired. The magazine 44 sets on an angle with a forward, upward incline with the front end connected 50 with the upper end of a belt elevator 45 car-

rying cups 46 adapted for the reception of a ball. The belt elevator 45 is supported by a shaft 47 mounted at the end 44^a of the magazine 44 and rotatably mounted in the bearing 48 (Fig. 13) at the top of a pedestal 49. The lower end of the belt elevator 45 is mounted on an idler shaft 50. The shaft 50 is rotatably mounted in the bearings 51. Near the end 44^b of the magazine 44 and in close proximity to the opening 40 into the hub portion 22^b is a gate construction comprising a lever 52 fulcrumed to a pivot 53 supported by a bracket 54 attached to the wall of the magazine 44 as at 55. To the end of the lever 52 are pivoted, as at 56, upwardly extending pins 57 and 58 respectively penetrating the wall of the magazine 44 through openings 59 therethrough. A coil spring 60 connects the lever 52 and the wall of the magazine 44 as at 61 in such a manner as to normally hold the pin 58 in a position protruding a substantial distance into the magazine 44 as shown in Fig. 7 so as to retain the balls 62 in the magazine 44. The lever 52 is of sufficient length to space the pins 57 and 58 apart the distance necessary to retain a ball therebetween. A cable 63 is attached at one end to the lever 52 at 64, extends downwardly and is attached at the other end to the end 65^a of a bell-crank lever 65 pivotedly fulcrumed to the end of the shaft 66 supporting one of the rollers 19. Attached to the end 65^b of the lever 65 is a cable 67 extending to the front end 68^a of the alley floor 68 where it is connected to the end 69^a of a lever 69 pivotally fulcrumed as at 70. The end 69^b of the lever 69 is set at an angle as shown in Fig. 16. The belt elevator 45 is preferably inclosed in a casing 71 (Fig. 16).

75 Referring now to Fig. 12, the casing 17 is combinedly supported by the shoe 18 resting on the rollers 19 and by a pedestal 72 having bearings 73 which support the shaft 38, to which shaft 38 are rotatably secured the arms 74 of the bracket 75. The bracket 75 is rigidly secured to the casing 17 as at 76, the part 77 being added to make more rigid such connection. Extending downwardly from the bottom portion of the casing 17 (Fig. 16) is a lug 78 to which is attached a cable 79 extending to the front end 68^a of the alley floor 68 where the same is attached to the end 80^a of the lever 80 pivotally fulcrumed at 81. To the lever 80 is attached a latch 82 adapted for engagement with a rack 83. Attached also to the lug 78 is a coil spring 78^a joined to a fixed position as at 78^b.

80 Referring now to Figs. 12, 13 and 14, to the shaft 47 is secured a band-wheel 83. A belt 84 is passed over the band-wheels 39^a and 83 and a belt 85 engages the band-wheel 39 and reaches to a source of power. Arranged in an upright position in front of the casing 17 (Fig. 16) is a canvas 86 represent-

ing a base-ball field, upon which is diagramed a diamond 87 showing first, second, third and home bases and a pitcher's box 92, which is an opening through the canvas 86. 5 Upon canvas are also diagramed fields 93, 94, 95 and 96. Mounted on the top of the casing 17, as at 97, is a bracket 98 having a bearing 99 in which is rotatably and slidably mounted a rod 100. Said rod 100 also having a loose bearing 101 in the curtain 86 through which it extends and having rigidly secured thereto on the side 86^a of the curtain 86 a disk 102 adapted to normally cover the opening 92 through said canvas. The alley 15 floor 68 (Fig. 16) is built on an incline with a sudden drop downward, as at 103, at the rear end thereof in close proximity to the entrance 104 of the elevator casing 71.

Extending outwardly from the rod 100 is 20 an arm 105 to which is attached a cable 106 having its opposite end attached to the end 65^a of the lever 65. The elevator floor 68 is inclined toward the center in cross section as to the point 109 (Fig. 15) which is the 25 point on the alley floor 68 nearest the entrance 104 to the elevator 45.

In the practical operation of the device, a 30 batter or catcher takes his position at the end of the alley floor 68, as at 110 facing the canvas 86 representing the base-ball field and substantially in line with the end 25^a of the barrel 25. The power operating the belt 35 45 in set in motion and the shafts 38 and 47 are set to rotating causing the belt elevator 40 45 and the arms 23 to rotate. A number of 45 balls 62 are tossed forward onto the alley floor 68 which find their way by gravity to the entrance 104 of the elevator 45 and are picked up by the cups 46 of the elevator 45 50 by which they are carried upwardly and deposited in the magazine 44, they traveling 44^b therein by gravity to the end 44^b thereof, and are stopped by the pin 58. When the batter or catcher is ready at his position, 110 to take 55 care of the balls 62, the operator of the apparatus presses his foot on the end 69^b of the lever 69, which through the action of the lever 69, the cable 67, the lever 65, the cable 63 and the lever 52 draws downwardly the 50 pin 58 (Fig. 7) and throws upwardly the pin 57 permitting one ball 62 to escape from the magazine and pass by gravity through the opening 40 in the hub portion 22^b (Fig. 4) and into the space 42^a between the inner ends 55 of the arms 23. The ball 62 then passes by gravity to a position in front of the segments 42 and by the rotation of said segments with the hub 22 the ball is carried around and by centrifugal force thrown into the entrance 60 24^a of the spiral groove 24 where it is picked up and forced along the path of the said spiral groove in the direction of the arrows (Fig. 18) to the tangentially arranged barrel 25. There the end 23^a of one of the 65 arms 23 gives it a final throw forcing it at

a high rate of speed through the barrel 25 toward the position 110 near the front end of the alley floor 68 where the player either endeavors to catch or bat the same. If the ball is batted to the positions of the field 93 70 on the canvas 86 the same is reckoned a foul ball, if to the portion 93^a within the diamond 87 the same is reckoned as a one base hit, if batted to the portion 94, it is reckoned a two base hit, if batted to the portion 95, it is 75 reckoned a three base hit and if to the portion 96 it is reckoned a four base hit.

As stated before the disk 102 (Fig. 15) normally covers the opening 92 through the canvas 86 directly in front of the end 25^a 80 of the barrel 25 of the casing 17, but the cable 106 connected by arm 105 to the rod 100 to which the disk 102 is rigidly secured, being secured to the same lever 65 that is operated to release the ball 62, when the lever 69 is operated to throw the ball the disk 102 is rocked sidewise by the throwing of the cable 106 to the position shown in Fig. 15 leaving a clear path for the ball to pass through the opening 92 in the canvas 86. 90 When the lever 69 is released the coil spring 60 (Fig. 7) returns the pin 58 to the position shown and gravity returns the disk 102 to the position shown in Fig. 16 over the opening 92 so that a ball can not be batted 95 therethrough. The swinging sidewise of the disk 102 from its normal position over the opening just as the ball starts into the casing 17 gives warning to the batter or catcher as to when to expect the ball. When it is 100 desired to change the angle of the ball, the lever 80 connected by the cable 79 to the lug 78 is operated to rotate the casing 17 to direct the barrel 25 downward from the horizontal or upward as indicated by the dotted 105 lines 25^b (Figs. 6 and 16).

Referring again to Fig. 7: When the lever 52 is operated to draw downwardly the pin 58, the pin 57 penetrates the interior of the magazine 44 to measure off one ball in the 110 magazine 44 to permit only one ball 62 to escape from the magazine by one operation of the lever. The batted balls after striking the canvas 86 fall to the alley floor 68 and by gravity find their way to the entrance 115 104 of the elevator 45 by which they are again returned to the magazine 44 to be re-thrown.

Referring now to Figs. 1 and 5, the ball 62 by centrifugal force naturally follows the wall 24^b of the spiral 24 in its passage therethrough which causes the ball to rotate clock-wise giving the same what is known as the down-curve. Means are provided in the barrel 25 for neutralizing this curve and for providing an upward curve, a right hand and a left hand curve. To neutralize said down curve so as to throw a straight ball, the cable 37 in the bottom wall 25^a of the barrel 25 is manually drawn downwardly 120 125 130

slightly causing the lever 35 to operate against the pin 30 to force the fibrous strip 27 slightly into the path of the ball in its passage through the barrel 25. If an upward curve is desired to be given the ball, then the strip 27 is forced in the same manner slightly farther in the path of the ball. In like manner the strips 27 in the side walls 25^a and 25^e may be thrown into the path of the ball to give the same a left or a right hand curve. The speed of the ball 62 is regulated by the velocity of the shaft 38 which may be regulated as desired. When the cables 37 (Fig. 5) are released the coil 15 springs 36 return the fibrous strips to the position shown. The dotted line 27^b merely indicates the path of the portion 27 in its entrance into the path of the ball through the barrel 25. Between the lever 80 and the 20 base 110 is an upright screen 111 for the purpose of stopping a ball thrown from the apparatus providing the same is not struck or caught by the batter or catcher.

What is claimed is,

- 25 1. A ball throwing apparatus comprising an upright casing, mounted on rollers adapted to rotate on bearings, a transversely arranged centrally disposed opening therethrough, grooves in the inner walls of said casing beginning at the outer edge of said opening and extending outwardly in a spiral, a horizontally arranged barrel reaching through the end wall of said casing and connected with said spiral, a hub in said 30 centrally disposed opening composed of two horizontally arranged parts spaced apart to provide an opening through the side of one of said parts, a shaft attached to the other of said parts, arms radiating from said hub on the inside of said casing and reaching outwardly beyond said spiral grooves and to a point in said barrel and means for rotating said shaft, together with means for tipping said disk to uncover said opening at approximately the time a ball is fed to 35 said apparatus.
- 35 2. A ball throwing apparatus, comprising an upright casing, a supporting means therefor, a transversely arranged centrally disposed opening therethrough, grooves in the inner walls of said casing beginning at the outer edge of said opening and extending outwardly in a spiral, a horizontally arranged barrel reaching through the end wall of said casing and connected with said spiral, a hub in said centrally disposed opening composed of two horizontally arranged parts spaced apart to provide an opening 40 therebetween, an opening through the side of one of said parts, a shaft attached to the other of said parts, arms radiating from said hub on the inside of said casing and reaching outwardly beyond said spiral grooves and to a point in said barrel and means for rotating said shaft, together with means for tilting said 45 casing to change downwardly or upwardly from the horizontal the angle of said barrel, such means comprising a lug attached to the bottom of the casing to which is attached a cable extending forward and to 50 which is also attached a coil spring extending rearward and secured to a permanent position whereby by the drawing forward of the cable the barrel of the casing is elevated and by the release of the cable the 55 barrel is lowered by means of the tension of the spring turning backward the casing.
- 55 2. A ball throwing apparatus, comprising an upright casing, a supporting means therefor, a transversely arranged centrally disposed opening therethrough, grooves in the inner walls of said casing beginning at the outer edge of said opening and extending outwardly in a spiral, a horizontally arranged barrel reaching through the end 60 wall of said casing and connected with said

spiral, a hub in said centrally disposed opening composed of two horizontally arranged parts spaced apart to provide an opening therebetween, an opening through the side of one of said parts, a shaft attached to the other of said parts, arms radiating from said hub on the inside of said casing and reaching outwardly beyond said spiral grooves and to a point in said barrel and means for rotating said shaft, together with 75 an alley floor upon the rear of which said apparatus is mounted, an uprightly mounted canvas in front of the barrel of said casing, an opening through said canvas in front of said barrel, a base at the front of said alley 80 floor and a screen in front of said base, together with a disk normally covering the opening through said canvas and means for tipping said disk to uncover said opening at approximately the time a ball is fed to 85 said apparatus.

3. A ball throwing apparatus comprising an upright casing, a supporting means therefor, a transversely arranged centrally disposed opening therethrough, grooves in the 90 inner walls of said casing beginning at the outer edge of said opening and extending outwardly in a spiral, a horizontally arranged barrel reaching through the end wall of said casing and connected with said spiral, a hub in said centrally disposed opening composed of two horizontally arranged parts spaced apart to provide an opening 95 therebetween, an opening through the side of one of said parts, a shaft attached to the other of said parts, arms radiating from said hub on the inside of said casing and reaching outwardly beyond said spiral grooves and to a point in said barrel and means for rotating said shaft, together with 100 means in said barrel for regulating the curve of the ball thrown therethrough, to give such ball a neutral, upward, downward, right-hand and left-hand curve.

4. A ball throwing apparatus comprising 110 an upright casing, a supporting means therefor, a transversely arranged centrally disposed opening therethrough, grooves in the inner walls of said casing beginning at the outer edge of said opening and extending 115 outwardly in a spiral, a horizontally arranged barrel reaching through the end wall of said casing and connected with said spiral, a hub in said centrally disposed opening composed of two horizontally arranged parts 120 spaced apart to provide an opening therebetween, an opening through the side of one of said parts, a shaft attached to the other of said parts, arms radiating from said hub on the inside of said casing and reaching 125 outwardly beyond said spiral grooves and to a point in said barrel and means for rotating said shaft, together with means in said barrel for regulating the curve of the ball thrown therethrough, to give such ball

a neutral, upward, downward, right-hand and left-hand curve, such means comprising fibrous strips mounted in recesses in the inner wall of said barrel and adapted for being thrown into said barrel in the path of a ball passing therethrough to cuff the same to effect such curve.

5. A ball throwing apparatus, comprising an upright casing, a supporting means therefor, a transversely arranged centrally disposed opening therethrough, grooves in the inner walls of said casing, beginning at the outer edge of said opening and extending outwardly in a spiral, a horizontally arranged 10 barrel reaching through the end wall of said casing and connected with said spiral, a hub in said centrally disposed opening composed of two horizontally arranged parts spaced apart to provide an opening therebetween, 15 an opening through the side of one of said parts, a shaft attached to the other of said parts, arms radiating from said hub on the inside of said casing and reaching outwardly 20

beyond said spiral grooves and to a point in said barrel and means for rotating said shaft 25 together with means in said barrel for giving a curve to a ball while passing therethrough.

6. A ball throwing apparatus comprising a casing having a passageway radiating from a central position therein outwardly and connecting with a tangentially extending barrel, means for forcing a ball through said passageway into and through said barrel, an uprightly mounted canvas in front of said barrel, an opening in the canvas in front of the same, a disk tiltably mounted to cover the opening in said canvas and means for tilting said disk to uncover said opening.

In testimony whereof I affix my signature 40 in presence of two witnesses.

JAY L. REYNOLDS.
